Application September 17, 1938, Serial No. 230,523

12 Claims. (Cl. 95—75)

This invention relates to photographic printing apparatus and has particular reference to printing apparatus wherein a developed printing film and a sensitized film being printed are continuously run in contact with each other across a printing light beam.

In contact printing, it is essential that intimate contact with minimum relative slippage, be maintained at the printing point between the printing film and the sensitized film being printed. This is especially true when printing sound tracks, in which case even a slight separation or relative movement between the films, i. e. .0005 inch causes distortion of the graphically produced sound modulations of the sound track.

Furthermore, it is essential, especially when printing sound tracks, to maintain an even printing illumination throughout the area being printed while preventing any reflection of the printing beam either internally of the films themselves or therebehind onto the sensitized film during the printing operations. Heretofore, when printing sound tracks from one film to another wherein, according to present day standards where the sound tracks are positioned directly adjacent one row of sprocket perforations, it has frequently been found that an unwanted 96 cycle modulation has been introduced into the sound track being printed. I have discovered that this 96 cycle modulation has been due largely to the printing light beam striking the edges of the sprocket perforations directly adjacent the sound track and thereafter reflecting back onto the sensitized film. This reflection, of course, occurred only at points opposite the sprocket perforations and thus caused fogging of the sound track on the sensitized films at regularly spaced areas. When the sound track film thus printed was subsequently reproduced, these regularly spaced, fogged areas of the sound track passed the reproducing point at the same frequency as the sprocket perforations, namely 96 times per second and thus produced a 96 cycle hum. I have discovered that this effect is especially noticeable where the printer light beam is flooded onto the film without the use of an optical system instead of being projected thereon. In this case, a large amount of the rays of printing light strike the film at an angle, and consequently strike the edges of the sprocket perforations in both the printing film and the sensitized film at an angle, causing an unwanted reflection of such light onto the sensitive film to fog the same.

Furthermore, I have discovered that when the films being printed were wrapped or guided

around an arcuate surface, they were minutely separated at the points where the sprocket perforations occur and that since the sound track is in immediate proximity to the perforations, the film along this track was also minutely separated at spaced intervals. This, of course, gave rise to distortion in printing. This minute separation between the films at the sprocket perforations was probably due to the slight burrs or raised edges formed around such perforations either during the perforating operation or by later warping of the films. Also, inasmuch as a film is stiffer across the "lands" intermediate the sprocket perforations than across the perforations themselves, the film, when wrapped around an arcuate or cylindrical surface will assume a polygonal shape instead of a perfect arc. The superposition of two of such polygonally shaped films over an arcuate surface tends to cause the films to separate slightly along the sprocket hole perforations and parts adjacent thereto, including the sound track, thus tending to separate the films.

Furthermore, due to the fact that the films assume a polygonal shape along the sprocket perforations as they are wrapped around an arcuate surface, the printing light beam, as it passes through the portion of the printing film directly adjacent the sprocket perforations, i. e. the sound track, on its way to the sensitized film is refracted in an irregular manner by such film due to the fact that the sound track portions of the films continually assume minutely different angular positions relative to the axis of the printing light beam as the films pass thereacross, thereby tending to distort the sound track printed on the sensitized film.

Accordingly, one object of the present invention is to obtain at the printing point an intimate contact between the pair of films being printed.

According to another phase of the invention, the films are passed over an arcuate surface at the printing point and are tensioned on either side thereof to maintain an intimate contact between the two films on such surface at the printing point. A rotatable toothed drum, forming a part of such arcuate surface, is provided to drive the films past the printing point. According to the present invention, the tension on the films on one side of the arcuate surface is maintained less than that on the other side to permit the drum to drive the films thereover while reducing the driving load on the teeth thereof.

Another object is to facilitate adjustment of an optical system for printing films.

Another object is to permit individual adjustment of the elements of an optical system for a printing apparatus while permitting adjustment of the optical system as a whole.

5 Another object is to photographically form identification marks on a film being printed simultaneously with the printing thereof from another film.

10 Another object is to regulate the color characteristics of a printing light.

Another object is to ventilate a printer lamp housing while preventing light leakage therefrom.

15 The manner in which the above and other objects of the present invention are accomplished will be readily understood on reference to the following specification read in conjunction with the accompanying drawings in which:

20 Fig. 1 is a side elevational view of a printing apparatus, with parts broken away, embodying the present invention.

Fig. 2 is a sectional plan view through the printing mechanism and is taken along the line 2—2 of Fig. 1.

25 Fig. 3 is a sectional view taken along the line 3—3 of Fig. 2.

Fig. 4 is a sectional, elevational view through the film driving mechanism of the printer and is taken along the line 4—4 of Fig. 3.

30 Fig. 5 is a sectional view through the edge number printing attachment and is taken along line 5—5 of Fig. 4.

Fig. 6 is an enlarged sectional view through the optical system for the printer and is taken along the line 6—6 of Fig. 3.

35 Fig. 7 is a front view of the pad roller and mount therefor and is taken in the direction of the arrow 7 of Fig. 4.

Fig. 8 is a sectional view showing the construction of the filter slide and is taken through the lens tube along the lines 8—8 of Fig. 6.

40 Referring particularly to Fig. 1 the printing machine comprises a casting 10 supported at the top of a standard 11 forming the support for the printing machine. A printer head casting, generally indicated at 12, is secured to one side of the casting 10 by bolts 13 and carries the various film driving and printing elements.

45 The printer head casting 12 comprises a bored semicylindrical protuberance 14 forming a printing compartment housing. A vertical wall section 15 integrally formed at one end of the housing 14 forms a bearing support for the various film driving elements.

50 The negative or printing film 16 is supplied by a supply reel 17 rotatably mounted in a manner not shown upon a standard 18 supported from the printer head casting 12. The printing film 16 after passing through the various film driving and printing elements is reeled upon a take-up reel 19 below the casting 12 and rotatably mounted in a suitable manner on a bracket 20 extending from the printer standard 18. The positive or sensitized film 21, on which images from film 16 are to be printed, is supplied by a supply reel 22 rotatably mounted above the printing mechanism by a suitable bracket (not shown) extending from the standard 18. Film 21, after passing through the various film driving and printing mechanisms is stored upon a take-up reel 23 also rotatably mounted upon bracket 20. These take-up reels 19 and 23 are driven through suitable slip clutches (not shown) by a continuously driven belt 24.

55 Referring now particularly to Fig. 4 the printer film 16 after passing from the supply reel 17 is

guided into contact with the sensitized film 21, led from its respective supply reel. These films are then led around a guide roller 25, around a feed or pull down sprocket 26, being maintained in an intimate contact therewith by a pad roller 5 27. Film 16, on emerging from the sprocket 26, is guided under a weighted roller 28, over a guide roller 29, and over a toothed printing drum 30 rotatably mounted in a transversely extending bore 31 formed in the housing 14 and comprising the printing compartment. A flat guide plate 32 tangentially aligned with the surface of the printer drum 30 is provided to guide the film 16 thereover.

55 The sensitized film 21, emerging from the sprocket 26, passes under a second weighted roller 33, around a guide roller 34 and is thence led into contact with the film 16 while passing over the drum 30. It will be noted that the film 21, on passing into engagement with the film 16 20 over the drum 30 converges therewith at an angle of approximately 5°. The provision of these converging paths of films 16 and 21 as they are led onto drum 30 permit the air therebetween to be continuously squeezed or wrung rearwardly 25 instead of being trapped therebetween to cause a separation of the films. This squeezing or wringing action is caused both by the tensioning of the films 16 and 21 over the drum 30 and by the pressure of a pad roller 136 against the two 30 films on the drum 30.

55 On emerging from the drum 30 the films 16 and 21 pass in contact with each other over a second flat guide plate 35 and thence around a weighted roller 36, over a hold back sprocket 37 35 being held in engagement therewith by a pad roller 38, thence over a guide roller 40 and thereafter onto their respective take-up reels.

60 The weighted roller 28 is rotatably mounted on the end of an arm 41, the other end of which 40 is pivotally journaled on the stationary shaft 29' of the roller 29. Shaft 29' is rigidly secured to the wall section 15 of casting 12. A weight 42 is provided on the arm 41 to cause the roller 28 to exert a tensioning effect of approximately 45 one pound on the film 16 intermediate the sprocket 26 and toothed drum 30. The weighted roller 33 is likewise mounted on an arm 43 which is pivotally mounted on a stationary shaft 34' of the roller 34. Shaft 34' is also rigidly secured to the wall section 15 of casting 12. A weight 44 on the arm 43 is provided to cause the roller 33 to exert a tension of approximately one pound and one-half on the film 21 intermediate the sprocket 26 and drum 30. The weighted roller 36, below the drum 30, is rotatably mounted on a shaft 36' rigidly secured at one end of an arm 45 which is pivotally mounted at the other end thereof on the shaft 37' of the sprocket 37. A tension spring 46 is mounted between the arm 45 60 and a point on the wall 15 to assist the weight of the roller 36 in maintaining a tension of approximately one-half pound on the two films 16 and 21 intermediate the drum 30 and the sprocket 37.

65 From the above it will be noted that due to the tensioning of the films above and below the toothed drum 30 an intimate contact between the films will be maintained while passing thereover. Furthermore, due to the fact that the tensioning effect is greater on the films above the printing drum 30 than below the drum, the sprocket teeth 50 of drum 30 will produce a driving effect on the films but with the tooth load thereon less than the tension applied to the films. That is, the leading edges of the sprocket 75

teeth 50 will engage the leading edges of the sprocket perforations of films 16 and 21 as the films pass over the drum 30. This maintains the films in accurate registration with each other. For this reason, I prefer to so adjust the film tension above and below the drum 30 that a minimum tooth load will be maintained to reduce film wear while providing a sufficient amount of such tooth load to maintain accurate registration of the films with the sprocket teeth 50. I have found that by providing a tooth load of approximately one pound for each film, such as results from employing the above mentioned tensioning values, satisfactory film registration 10 is obtained.

Also, since the tension in film 16 governs only the contact between film 16 and drum 30, while the tension in film 21 governs both the contact between the films 16 and 21 as well as the contact between these films and drum 30, I prefer to employ a greater tension in the film 21 than in film 16.

The loop in the two films 16 and 21 intermediate the drum 30 and the sprocket 37 is preferably so adjusted that the roller 36 resting therein assumes such a position that a line passing through the axis of rotation of roller 36 and the axis of pivotal movement of arm 37 lies perpendicular to the surface of the guide plate 35. Further, when in this position the guide plate 35 will be tangentially aligned at one end thereof with the surface of the drum 30 and at the other end thereof with the surface of the roller 36.

The two flat guide plates 32 and 35 are suitably secured to the housing or protuberance 14 at the base of an opening 47 formed therein. Opening 47 permits the films 16 and 21 to be led onto the drum 30.

It should be noted at this point that the rollers 29 and 34 are edge guiding rollers having spaced flanges as at 8 and 9, respectively, thereon to engage and guide the opposite edges of the films against lateral movement as they pass onto the drum 30. Thus each film will be individually edge guided, there being no provision for edge guiding of the films thereafter while in contact with each other.

Referring now to Figs. 2 and 3 the drum 30 is formed of a sprocket member 48 having a row of sprocket teeth 50 therearound, which member is integrally formed on a shaft 51 rotatably mounted in a bearing member 52. Bearing member 52 is secured within the bore 31, forming the printing compartment, by screws 53. A cylindrical flange 54 secured to the sprocket member 48 by screws 55 forms a rotatable film support for the picture portion of the films passing over the drum 30 while permitting the sound track portion of these films to overhang. A stationary ring member 55 is fitted within the bore 31 and is secured therein by screws 56. Ring 55 has a reduced cylindrical bearing portion 57 thereon of the same diameter as, and concentric with, film drum 30 to support the overhanging portion of the films passing over the drum 30 while being spaced from the open end of the flange 54 of drum 30 by an amount substantially equal to the width of the sound track. Preferably, however, the inner edge of the bearing portion 57 of ring 55 extends approximately .002" over the edges of the sprocket perforations directly adjacent the sound track to prevent the printing light beam from striking such edges. It will be noted that the adjacent edges of the flange 54 and ring 55 are chamfered as at 58. This provision for laterally supporting the films

throughout the entire width thereof except the sound track portions, eliminates any tendency of the film to bow transversely and therefore aids in maintaining an intimate contact between the films themselves and between the films and the drum 30 and bearing portion 57 of ring 55 at the printing point.

Describing now the drive for the sprockets 26 and 37 and drum 30, a helical gear 60 (Figs. 2, 3 and 4) is secured to the shaft 51 of drum 30 and is driven by a similar small gear 61 (Fig. 4) meshing therewith and secured in driving relation to a pulley 62 over which the continuously driven belt 24 is engaged. Gear 61 also meshes with a gear 59 affixed to shaft 37 of sprocket 37. A gear 63 secured to the shaft 26 of sprocket 26 is driven from the gear 60 by an intermediate idler gear 64. The shafts of gears 59, 61, 63 and 64 are all suitably journaled in bearings formed in wall section 15.

Referring to Figs. 2, 3 and 6, I will now describe the optical system for projecting a printing light beam onto the sound track portions of the films 16 and 21 while passing in contact in an arcuate path over the drum 30 and bearing portion 57 of ring 55.

The optical system comprises generally a lamp house 66 containing a printing lamp 67, a lens mount generally indicated at 68 having a prism 69 at the forward end thereof for deflecting the printing beam of light into the sound track portion of the films 16 and 21 intermediate the adjacent edges of the drum 30 and ring 55.

As shown in Fig. 6, the mount 68 comprises a cylindrical tube 70. A slit member 71 having a horizontally extending slit 72 formed therein is threadably secured in the rear end of the tube 70. Also threadably secured in this end of tube 70 is the mount for a condenser lens 73. The opposite end of tube 70 is securely fitted within the slide block 74, having a vertically extending slide aperture 75 extending therethrough. A tapered objective tube 76, co-axial with tube 70, is threadably mounted in the opposite end of the block 74 and carries at its forward end a pair of objective lenses 77. The size of the slit 72 and the magnification of the objective lenses 77 are such that a horizontal slit of light approximately .009" high and .010" long is focussed upon the films at the point P (Fig. 4). The length of this slit of light is therefore sufficient to extend entirely across the gap or opening between the adjacent edges of the drum 30 and ring 55. The right angle prism 69 is mounted in a prism block 79 having a bore therein fitted over the forward end of the tube 76. A set screw 79' threadably mounted within the block 70 permits the prism 69 and block 79 to be locked in any adjusted position about the tube 76.

As shown in Figs. 2 and 3 the tube 70 is slidably and rotatably mounted in a bushing 77 secured to and extending through an end plate or cover member 78. End plate 78 is secured across the bore 31 provided in the housing 14 by bolts 80 and 81. Bolts 80 and 81 extend through elongated horizontally extending slots 82 and 83, respectively, formed in the plate 78, permitting transverse adjustment of the plate 78 and mount 68, carried thereby, in a horizontal direction. A set screw 84, threadably mounted in the bushing 77, permits rotatable as well as longitudinal adjustment of the tube 70 and the lamp house 66 carried thereby.

Referring now to Figs. 3, 6 and 8, a filter slide, generally indicated at 85, is slidably mounted

within the aperture 75 in block 74. Filter slide 85 comprises a channel shaped member 86 having three spaced apertures 87, 88 and 89 formed therein, any one of which is adapted to be positioned, on movement of slide 85, in the path of light through the tube 70. The upper aperture 87 is in the form of a horizontal slit to reduce the amount of light passing therethrough, the other two apertures 88 and 89 being circular. A pair of flat glass blocks 90 and 91 having different color filtering values are mounted in the channel member 86 over the apertures 88 and 89, respectively. A cover plate 92 is mounted on the member 86 by screws 92' over the blocks 90 and 91 to retain the same in place. Apertures 93 and 94 are provided in the cover plate 92 to permit transmission of light through the blocks 90 and 91, respectively. The aperture 93 is in the form of a horizontal slot to reduce the amount of light passing therethrough. These filter blocks 90 and 91 may have any desired color absorbing characteristics. For example, block 90 passes only ultra violet light and is inserted in the path of the printing light beam through the tube 70 whenever ultra violet printing is to be employed, while the block 91 permits only the blue component of the printing light to pass therethrough and is inserted in the printing light beam whenever fine grain film is to be printed. The slide 85 is manipulated from the exterior of the printer housing 14 by means of a rod 95 loosely mounted on a transversely extending pin 96 secured in the opposite legs of the channel member 86. Rod 95 extends through an aperture in the upper wall of housing 14 and thence extends loosely through a block 97 (Fig. 3) secured in a suitable manner on top of the housing 14. A series of three circumferential slots 98, 99 and 100 are formed at spaced intervals along the rod 95 and are adapted to be selectively engaged by a plunger member 100 slideable transversely in the block 97 and urged against the rod 95 by a spring 101. When one or the other filter blocks 90 and 91, or the aperture 87 is to be moved into position in the printing light beam, the plunger 100 is retracted from engagement with one of the slots 98, 99 or 100, and the rod 95 is moved vertically until the correct aperture or filter block is positioned in the tube 70. The plunger 100 is then allowed to engage the corresponding slot 98, 99 or 100 to hold the filter slide 85 in its correctly adjusted position. A considerable amount of loose play is provided between the rod 95 and the aperture in the block 97 through which it slides, whereby the tube 70 may be adjusted longitudinally to correctly align the optical system with the sound track portions of the films being printed. Also, a considerable amount of play is provided between the lower end of the rod 95 and the pin 96, on which it is pivotally secured, whereby the tube 70 may be transversely and rotatably adjusted slight amounts to correctly align and focus the optical system on the films 16 and 21. It will be understood, of course, that transverse adjustment of tube 70 will cause a change in the focus of the projected beam of light passing therethrough due to the right angle deflection of the beam by the prism 69.

As will be noted in Figs. 1, 2 and 3 the printer lamp housing 66 comprises a vertically extending cylindrical shell 105 having a crescent shaped supporting member 106 surrounding the same and secured thereto by screws 106'. A bushing 107 extending through both the member 106 and shell 105 is adjustably fitted over the outer end of the tube 70 and has a set screw 108 threaded therein

whereby the lamp house 66 is supported by tube 70 and may be adjusted longitudinally and rotatably about the tube 70.

The base of the lamp house 66 comprises a cylindrical end cover member 109 fitted with the shell 105 and secured thereto by screws 110. A pair of spaced circumferentially extending channels 111 and 112 are formed around the member 109. A series of spaced vent holes 113 extend between the channel 111 and the interior of the housing 66. A second series of vent holes 114 extend between the channels 111 and 112 and are staggered in relation to the other holes 113 as shown in Fig. 2. A third series of vent holes 115 are formed in the shell 105 and communicate with the channel 112 in staggered relation to the apertures 114. The labyrinth air venting passage thus formed permits air to pass into the lamp housing 66 while preventing leakage of printing light therefrom. The upper end of the shell 105 is closed by a cover member 116 having a tubular extension 117 formed centrally thereof and defining an opening. A flexible hose 118 is fitted over the extension 117 and is connected to a suitable vacuum pump (not shown) to draw cooling air through the lamp housing 66 from the labyrinth passage at the base thereof to cool lamp 67.

Lamp 67 is mounted in a socket 119 fitted in an opening 120 formed in a lamp supporting plate 121 which is secured to the base member 109 by screws 122. A set screw 123 threadably mounted in the plate 121 permits vertical and rotatable adjustment of the socket 119 to correctly align the filament 67' of lamp 67 with the optical system in the mount 68. In lieu of a single filament lamp as illustrated, I may employ a multi-filament lamp. Lamp 67 is connected to a suitable source of supply by a conductor 120 and has a rheostat generally indicated at 171 (Fig. 1) in circuit therewith. Rheostat 171 is suitably secured to the casting 11 within easy reach of the operator of the printing machine.

From the foregoing it will be seen that the entire optical system, including the printing lamp 67, for printing the sound tracks of the films 16 and 21 is supported by the tube 70, carried by the end plate 78. Thus, the provision for lateral adjustment of the end plate 78 as well as the provision for longitudinal and rotatable adjustment of the tube 70 permits an adjustment of the entire optical system as a whole. Also, the provision of the set screw 79 in the prism mount 79 as well as the set screws 123 in the lamp housing plate 121 and the set screw 108 in the lamp supporting bushing 107, and movable filter slide 85, permits adjustment of the various elements of the optical or light projecting system individually.

Referring now to Figs. 2, 4 and 6, I will now describe the means for exposing identification marks on a sensitized film whereby to identify the particular printer in which such film was printed. A groove or notch 125 (Fig. 6) is formed at one point within the printing drum 30. A small passage 126 communicates this groove 125 with a point on the circumference of the drum 30 intermediate two of the sprocket teeth 50. This passage 126 is adapted to transmit light from a small lamp 127 to the films 16 and 21 at each revolution of the drum 30. Lamp 127 is mounted in a housing 128 secured on a bracket 129 supported on the filter slide block 74 by screws 130. A light passage 131 is formed at the front of the housing 128 to direct a pencil or beam of light from the lamp 127 toward the circular path 75

of movement of the passage 126. An arcuately shaped light shield 132 (Figs. 4 and 6) is secured to the lamp housing 128 to prevent reflection of light from the lamp 127 onto the sound track portion of the films being printed. The edge 133 of shield 132 lies closely adjacent the inner surface of the drum 30 so that any light passing therebetween is not in line with the films being printed. Current is supplied to the lamp 127 through a conductor 134 passing through an aperture in the cover plate 78 and connected to a suitable source of current supply. It will be seen, therefore, that when the passage 126 passes beneath the line of light from the lamp 127, on each revolution of the drum 30, light will be transmitted to the films 16 and 21. Since, according to present practice, the space intermediate the sprocket perforations is generally left transparent, the light will pass through the negative or printing film 16 and thus fog or expose an identification mark on the film 21 at a point intermediate two of the sprocket teeth 30. By arranging any number of passages 126 or by varying the shape of such passages, different identification marks may be provided for different printer machines.

To further obtain an intimate contact between the two films 16 and 21 at the printing point, a pad roller 136 (Figs. 2, 4, 6 and 7) is provided. Roller 136 engages the films at a point directly opposite the printing point P and straddles both the drum 30 and the bearing portion 57 of stationary ring 55. A self-aligning mount, generally indicated at 137, is provided to resiliently urge the roller 136 against the films in contact. Mount 137 comprises a stirrup 138 in which the shaft of roller 136 is rotatably mounted. Stirrup 138 has a vertically extending bearing formed therein which is pivotally fitted over a bearing portion 140 formed at the bottom of a rod 141. Rod 141 extends through an aperture formed in a swivel block 142 and is adjustably secured therein by a set screw 143 permitting vertical adjustment of the roller 136. Block 142 has a horizontally extending bearing stud 144 thereon journalled in a bearing block 145 which is secured as by screws 145' to a gate member 146. Gate member 146 is pivotally mounted upon a stationary bearing stud 147 projecting from the wall 15 permitting movement of the roller mount 137 toward and away from the drum 30 for film threading purposes. Roller 136 is resiliently urged against the films 16 and 21 by a tension spring 148 extending between the upper end of rod 141 and a piece 149 secured to the pad member 146. A stop pin 150 is threadably mounted in the piece 149 for longitudinal adjustment thereof. The head of pin 150 is adapted to engage the rod 141 to limit the inward movement of the roller 136. Pad member 146 is limited in its inward movement by a set screw 151 (Fig. 2) and is adapted to be held in that position by a spring 153 (Fig. 4). Spring 153 surrounds a plunger rod 154 pivotally mounted at the upper end thereof to a dependent lug 155 integrally formed on the pad member 146 below the stud 147. Spring 154 engages at one end thereof a flange 156 formed on the rod 154, and at the other end thereof a sleeve 157 through which the rod 154 is slideable. Sleeve 157 is seated upon a semi-cylindrical projection 158 forming a bearing for a shaft 159. Projection 158 also has an aperture 162 in which the rod 154 is loosely mounted to slide therethrough. Shaft 159 has a radially extending hole 160 therein which, when aligned with the rod 154, permits the same to

project therethrough. Shaft 159 is adapted to be rotated by a handle 161 (Fig. 1) to align the hole 160 with the rod 154, thus permitting the rod 154 to extend into the hole 160 for the purpose of moving the gate member 146 into 5 threading position. Spring 153 acts as a snap-over spring to hold the gate member 146 in an open position away from the opening 47 in housing 14 when the gate member 146 is moved counterclockwise approximately 90°. 10

A switch (not shown) in circuit with the printing lamp 167 is actuated by the shaft 159. When the shaft 159 is rotated to align the hole 160 with the plunger rod 154, this switch will be opened to extinguish the printer lamp. Thus, this switch 15 forms a safety feature, preventing the lamp from being illuminated until the gate member 146 is closed.

The edge printing device comprises a small box shaped lamp compartment 163 (Figs. 4 and 5) 20 secured to the rear of the lower guide plate 35 by screws 164. A printing lamp 165 supported in a socket 166 within the compartment 163 is adapted to project a beam of light through a small printing aperture 168 formed co-extensively through 25 the forward wall of the compartment 163 and the guide plate 35. This passage 168 is directly in line with the path of movement of the edge numbers along the film 16 to permit such numbers to be printed on the sensitive film 21. A suitable 30 switch (not shown) is provided in the circuit of lamp 165 to open such circuit when it is not desired to print edge numbers. A mask 167 is integrally mounted on a pin 168 journalled in a bearing lug 169 projecting from the wall of compartment 163 and, when moved into one position, intercepts the line of light passing through the passage 168 and the films 16 and 21 to prevent the same from fogging the sensitized film 21 after passing therethrough due to reflection from 40 various metallic surfaces behind the films. Mask 167 is rotatable into an out-of-the-way position to permit threading the films in the machine. 35

Certain features disclosed herein are disclosed and claimed in my co-pending application 249,956, 45 filed January 9, 1939, for "Film printing apparatus" and in my U. S. Patent 2,199,764, granted May 7, 1940, for "Film marking apparatus."

I claim:

1. In a film printing apparatus, a rotatable 50 film supporting member having a cylindrical flange thereon, said flange being adapted to support a film with a portion of said film overhanging said flange and said flange having an aperture extending therethrough, a light source, an 55 optical system for projecting a beam of light from said light source onto said overhanging portion of said film on said flange, a mount for said optical system, a second light source, means on said mount for supporting said second light 60 source within said flange, said light source being directed toward the path of movement of said aperture, and a shielding member intermediate said second light source and the overhanging portion of said film. 65

2. Printing apparatus comprising the combination of a hollow drum adapted to support films in printing relation, said drum having a closed end and an open end and means for rotatably supporting said drum, a set of sprocket teeth 70 around said drum adjacent the closed end thereof, an exposure aperture comprising a light passage extending from the interior to the exterior of said drum between adjacent ones of said sprocket teeth, means providing a light beam 75

therefor, means providing a light beam for printing sound track from one to the other of the films overhanging the edge of said drum and means for shielding one of said light beams from the other.

3. Printing apparatus comprising a hollow drum having a flange adapted to support a light sensitive film and another film in contact in printing relation beyond said flange, means associated with said drum for printing said light sensitive film, an aperture through said drum, and means inside of said flange and associated with said aperture for exposing an identification mark on said light sensitive film outside the printing area beyond said flange.

4. A film printing apparatus comprising a rotatable open drum defining one side of the printing area and adapted to guide a pair of films in contact thereover with the printing area and one edge of said films overhanging said drum, a hollow film guiding member concentric with and spaced from said drum for defining the other side of the printing area and for guiding the overhanging edges of said films, means projecting through said hollow film guiding member for projecting a beam of light substantially radially onto said films intermediate said drum and said hollow film guiding member at a printing point, and a pad member engaging said films on said drum and on said film guiding member at said printing point.

5. Film printing apparatus comprising the combination of a printer housing having a cylindrical bore therethrough, a rotatable film drum adapted to support a pair of superposed films thereover with one edge of said films overhanging said drum, means in said bore for rotatably supporting said drum, a supporting member concentric with said film drum for supporting the overhanging edge of said films, means for supporting said supporting member in said bore, a cover member for one end of said bore, an optical system at least partly within said bore and adapted to project a beam of light onto said films intermediate said drum and said supporting member, means on said cover member for supporting said optical system, and means whereby said cover member may be adjusted transversely of said bore to focus said optical system.

6. A film printing apparatus comprising a casing, a rotatable film drum in said casing adapted to support a pair of superposed films thereover in printing relation, means in said casing for rotatably supporting said drum, said casing having an opening therein, a cover member for said opening, an optical system for projecting a beam of light onto said films on said drum, a mount for said optical system, means on said cover member for supporting said mount, said mount having an opening therethrough, a filter slide in said opening, and actuating means extending through said casing for manipulating said filter slide.

7. A printing apparatus comprising a casing having a cylindrical bore therein, a film drum in said bore adapted to support a pair of films in contact thereover with a portion of said films overhanging said drum, bearing means in said bore at one end thereof for rotatably supporting said drum, a stationary cylindrical member in said bore adapted to support the overhanging

portions of said films, said stationary supporting member being spaced from said drum to define a sound track printing opening, a cover member for the other end of said bore, an optical system adapted to project a slit of light and arranged substantially co-axial with said drum, a light deflector for deflecting a beam of light from said optical system onto the sound track portion of said films, a mount for said optical system and said deflector, said mount extending through said cover member, means on said cover member for securing said mount thereto, a lamp house, means for securing said lamp house on said mount, and a lamp in said lamp house for projecting light through said optical system.

8. Printing apparatus according to claim 7 comprising means whereby said mount may be adjusted longitudinally through said cover member.

9. Film printing apparatus comprising a film drum having sprocket teeth thereon, feed sprocket means for leading films in printing relation onto said drum, means for printing from one of said films to the other at said drum, take-up sprocket means for leading said films off of said drum, a synchronous power drive coupled to said drum, said feed sprocket means and said take-up sprocket means, means for guiding said films over said drum in an arc, means for tensioning the portion of said films intermediate said drum and said feed sprocket means, and simultaneously operative means for tensioning the portion of said films intermediate said drum and said take-up sprocket means to a lesser degree than said first mentioned tensioning means.

10. Film printing apparatus according to claim 9 wherein the tension in the outer of said films at said drum is greater than the tension in the inner of said films at said drum.

11. Printing apparatus comprising a printing drum having sprocket teeth, means for traversing a pair of films in printing relation over said drum, a synchronous power drive coupled to said drum and to said traversing means, means for printing from one of said films to the other at said drum, and film tensioning means at opposite sides of said drum and intermediate said traversing means and said drum for simultaneously tensioning said films, said film tensioning means at one side of said drum being more effective than the film tensioning means at the other side thereof whereby one side of the sprocket holes of said films is caused to drag against the sprocket teeth on said drum.

12. Film printing apparatus comprising a printing drum having sprocket teeth, a feed sprocket and take-up sprocket at opposite sides of said drum for traversing a pair of films in printing relation over said drum, means for printing from one of said films to the other at said drum, means for synchronously driving said sprockets and said drum at the same peripheral speed, film tensioning means for both of said films intermediate said feed sprocket and said drum and intermediate said take-up sprocket and said drum for simultaneously tensioning said films wherein said film tensioning means comprises means for tensioning said films a greater amount at one side of said drum than at the other.

ALBERT W. TONDREAU. 70
